UNITED STATES PATENT OFFICE.

HARRY C. HAMES, OF LONDON, OHIO, ASSIGNOR TO GEORGE P. PIERCE, OF KANSAS CITY, MISSOURI.

SILO.

1,286,300.

Specification of Letters Patent.

Patented Dec. 3, 1918.

Application filed October 22, 1915. Serial No. 57,306.

To all whom it may concern:

Be it known that I, HARRY C. HAMES, a citizen of the United States, residing at London, in the county of Madison and State 5 of Ohio, have invented certain new and useful Improvements in Silos, of which the following is a specification.

My invention relates to silos and has particular application to a door construction 10 whereby this door may be held closed and also may be the means of anchoring the usual type of circumferential reinforcing rod.

The main object of my invention consists 15 in a peculiar type of framework construction for the door, this portion of my invention consisting of the general framework with a concrete or cement block cast about it and, therefore, forming an integral part 20 of the concrete slab.

A further object of my invention resides 25 in the provision of a peculiar type of locking clip with which the locking bar for holding the door in closed position coöperates and into which the ends of the circumferential reinforcing rods are anchored, so that 30 these rods need not be extended across the door space. In this manner no obstruction is placed across the door to interfere with the discharging of the material from the 35 interior or to interfere with the free movements of an individual when entering.

The preferred embodiment of my invention is shown in the accompanying sheet of 40 drawings, in which similar characters of reference designate corresponding parts, and in which:

Figure 1 is a face view of a portion of a silo side wall showing the type of door 45 construction proposed by me,

Fig. 2 is a transverse section taken on line 2—2 of Fig. 1,

Fig. 3 is a detail view in perspective of the locking clips used by me and showing 45 the ladder rungs in position thereon, and

Fig. 4 is a detail cross sectional view of the joint formed between the door frame and the door.

The type of silo door illustrated in the 50 drawings, is particularly applicable to silos constructed from concrete or stone slabs placed one upon another and preferably made so that the joints are broken. These slabs are designated by the reference number 1 and extending vertically at one

point in the silo body, there are a plurality of superposed concrete slabs 2 of somewhat larger construction, these slabs being preferably square and having an annular door frame 3 cast within them. The peripheral edges of these door frames are preferably bent outwardly, as is shown at 4, both for the purpose of securely holding the frames in position, and the inside flanges are each provided with a V-shaped bead 4^a for the purpose of forming a tight joint between them and the doors 5. These doors are also formed with a semi-circular bead 6 so shaped that their inner edge is in engagement with the inner edge of one of the flanges 4, while the remainder of the beads are slightly spaced from the door frame in order to form a space into which clay or the like may be placed when the door is placed in position to exclude all air and moisture. Each of the doors is also provided with a locking bar 7 centrally pivoted as is shown at 8 and engaging inclined or cam faces 9 of the locking clips shown at 10. These locking clips are each provided with a pair of rearwardly extending lugs or pins 11 designed to pass through the corresponding apertures formed in each of the door frames 3 and during the operation of casting the concrete about these door frames, 35 these clips may be placed in position so that they will be permanently attached. However, if desired, the holes formed in the concrete by the pins 11 may be so shaped that the clips will at all times be removable. The ends of the clips 10 opposite from those on which the cam surfaces 9 are formed, 40 are bent rearwardly as is shown at 12 to extend in substantially the same direction as the direction of the silo body and these 45 portions 12 are then again bent inwardly as is shown at 13. These inwardly bent portions are also notched or cut out as is shown at 14 to embrace or fit over the circumferentially extending reinforcing rods 100 15. In order that these reinforcing rods may not extend across the open doorway, I have provided each of the clips with an aperture 16 through which the threaded ends of these rods are made to pass and the 105 rods then firmly held in position by tightening of the nuts 17. The purpose of the inwardly bent portions 13 of the locking clips 11 will now be apparent, since tightening of the nuts 17 will tend to cause a 110

bending of these clips. The inwardly bent portions 13 then serve as a foot or abutment for resting against the outside face of the silo body to give sufficient stability to the 5 clips to permanently hold the reinforcing rods in position and to permit these rods to perform their reinforcing function. Also, these reinforcing rods are made to extend beneath the portion 12 of the clips in order 10 that they may pass very close to the outside face of the silo body in order that each of the blocks comprising this silo body may be engaged for purposes of reinforcement.

Since it is necessary to climb to the top 15 of these silos quite frequently, a ladder is very often necessary and in order to provide this ladder, I have so formed the wires 18 and 19 that they may be suspended from the locking clips in the manner shown. It will 20 be noted that the vertically extending ends of each of these ladder rungs is bent over to assume hook form, as shown at 20 and it is these hook formations that engage the portion 12 of each of the locking clips.

25 From the foregoing, it will be apparent that I have provided a particularly effective type of silo door. By casting the door frames into the slabs 2, these door frames are always permanently held in position 30 and the chances of their warping or becoming broken is reduced to a minimum. Further, by the peculiar type of locking clip shown the entire silo body may be reinforced through the medium of the reinforcing rods 35 15 and these clips also made to perform their function of coöperating with the locking bars 7 to hold the doors 5 in position.

What I claim, is:

1. In a silo, a door framework, a door fitting within said framework, a pair of locking clips carried by said framework, a split reinforcing rod extending circumferentially around the silo, means for anchoring the ends of said rod into said clips so as not to 40 pass over the door opening, and means also coöperating with said clips for locking the door in its closed position.

2. In a silo, a door framework, a door fitting within said framework, a pair of locking clips carried by said framework, a split reinforcing rod extending circumferentially around the silo, means for anchoring the ends of said rod into said clips so as not to 45 pass over the door opening, means also coöperating with said clips for locking the door in its closed position, and a ladder rung structure also supported from said pairs of clips in such manner as to be removable from in front of the door opening.

50 3. In a silo, a door framework, a door fit-

ting within said framework, a locking bar structure carried by said door, a pair of locking clips carried by said framework, one end of each of said clips being provided with a cam surface to coöperate with said 65 locking bar structure to hold the door in locked position, a split reinforcing rod extending circumferentially around the silo, said clips also having openings through which the ends of said rod may pass, and 70 means for securely anchoring the ends of said rod through the openings in said clips so that the rod does not pass over the door opening.

4. In a silo, a door framework, a door for 75 said framework, a locking bar for said door, a pair of apertured locking clips carried by said framework, one end of each of said clips being turned inwardly to coöperate with said bar and the other end of each of 80 said clips being bent rearwardly to extend in the same general direction as the silo body and then inwardly toward the silo, and a reinforcing rod extending circumferentially around the silo, the ends of said rod 85 being secured in said apertures and the inwardly bent portions of said clips having portions cut out to permit the passage of said rod.

5. In a silo, a door framework, a door for 90 said framework, a locking bar for said door, a pair of apertured locking clips carried by said framework, one end of each of said clips being turned inwardly to coöperate with said bar and the other end of each of 95 said clips being bent rearwardly to extend in the same general direction as the silo body and then inwardly toward the silo, a reinforcing rod extending circumferentially around the silo, the ends of said rod being 100 secured in said apertures and the inwardly bent portions of said clips having portions cut out to permit the passage of said rod, and ladder rungs shaped to be hung from 105 said clips.

6. In a silo, a door framework, an outwardly extending flange on the inside edge of said framework, a bead on said flange, a door for said framework, a bead around the edge of said door slightly larger in size 110 than the size of said first named bead, and means for locking said door and said framework together.

In testimony whereof I affix my signature in presence of two witnesses.

HARRY C. HAMES.
